United States Patent Office

Des. 220,748
Patented May 18, 1971

220,748

BOTTLE

Jerome Gould, Encino, Calif., assignor to Johnson & Johnson

Filed June 1, 1970, Ser. No. 23,240

Term of patent 14 years

Int. Cl. D9—01

U.S. Cl. D9—82

FIG. 1 is a side elevational view of a bottle showing my new design thereof with the bottle resting on its base;

FIG. 2 is a front elevational view thereof with the bottle resting on its base;

FIG. 3 is a side elevational view with the bottle resting on its top; and

FIG. 4 is a front elevational view of the bottle resting on its top.

I claim:
The ornamental design for a bottle, as shown.
